UTILITY VEHICLE

Kenneth P. Folks, Orlando, Fla.

Application June 29, 1956, Serial No. 42,083

Term of patent 14 years

(Cl. D14—3)

Fig. 1 is an elevational view from the right side of a utility vehicle having three wheels and embodying my new design;

Fig. 2 is a front elevation of the utility vehicle shown in Fig. 1 and illustrating a single front wheel at the center and the two rear wheels at either side of the center;

Fig. 3 is a rear elevation of the utility vehicle shown in Figs. 1 and 2 and illustrating a single front wheel at the center and the two rear wheels at either side of the center; and

Fig. 4 is a top plan view of the utility vehicle shown in Figs. 1, 2 and 3.

The dominant features of my design reside in the portions shown in full lines.

This application is a continuation-in-part of my application Serial D-40,028 filed February 3, 1956, now abandoned.

I claim:

The ornamental design for a utility vehicle, as shown and described.
